CONTINUOUS ICEMAKING APPARATUS

Alfred G. Janos, Erie, Pa., assignor to General
Electric Company, a corporation of New York

Application November 16, 1950, Serial No. 196,008

10 Claims. (Cl. 62—106)

1

My invention relates to ice-making apparatus and more particularly to ice-making apparatus adapted for the continuous production of ice.

It is an object of my invention to provide an improved apparatus for continuous production of ice.

It is another object of my invention to provide an improved apparatus for continuously producing and ejecting ice.

Further objects and advantages of my invention will become apparent as the following description proceeds and the features of novelty which characterize my invention will be pointed out with particularity in the claims annexed to and forming part of this specification.

In carrying out the objects of my invention, ice is continuously produced in the form of a cylindrical column within a refrigerated cylindrical chamber, the column of ice being progressively moved outwardly of the open end of the chamber and being broken off in any suitable manner into pieces of the desired size. It has previously been known to manufacture ice in the form of a continuous column but these previously-disclosed devices have used a reciprocating piston, or a continuously advancing piston which must ultimately be retracted, or have relied upon the pressure of the water supplied to effect movement and ejection of the ice column. In carrying out the objects of my invention I provide a continuously rotating cam having an irregular upper surface disposed at the bottom of the ice-producing chamber. As the cam is rotated it moves the column of ice upwardly, and water, which is continuously supplied to the space between the major portion of the cam and the ice column, continuously freezes to the portion of the ice column not at the time being engaged by the irregular cam surface. Thus, a layer of ice is continuously being added to the lower end of the column and, as the cam rotates, the ice-engaging raised portion of the cam progressively engages the newly-frozen portions on the lower end of the ice column effecting a lifting of the ice column. Thus, by my arrangement the cam may be rotated continuously, a layer of ice only a few thousandths of an inch thick being frozen onto the lower end of the ice column during the time required for the cam to make one revolution, and the overall ice column being advanced upwardly by the cam by the amount of the thickness of this layer of ice during each revolution of the cam.

For a better understanding of my invention, reference may be had to the accompanying draw-

ing in which Fig. 1 shows apparatus incorporating an embodiment of my invention; Fig. 2 is a view, partly in section, showing details of the construction of the ice-producing apparatus; Fig. 3 is a sectional plan view of the ice-producing chamber taken along the line 3—3 in Fig. 2; Fig. 4 is an enlarged view of the ice-producing chamber to illustrate the freezing of the ice and the lifting of the ice column by the rotating cam; and Fig. 5 is a plan view showing the upper surface of the cam.

Referring to the drawing, there is shown apparatus including a supporting base 1. On this base is mounted a conventional refrigerating unit comprising a motor-compressor unit enclosed within a hermetically sealed case 2. Compressed refrigerant is supplied from the refrigerating unit through a conduit 3 to a condenser 4. Liquid refrigerant flows from the condenser 4 through a restricting, or capillary, tube 5 to the ice-making structure 6, which is supported by legs 6a on the base 1. Vaporized refrigerant is returned to the refrigerating unit through a suction line 7.

The ice-making structure 6 includes a housing 8 of some suitable plastic or other material of low heat conductivity. A tubular element 9 formed of a metal of high heat conductivity forms the major portion of the ice-making chamber 10. The tubular element 9 is supported on a shoulder 11 of an upwardly extending ring 12 which is formed integral with the housing 8. The ring 12 and a portion of the bottom of the housing 8 form the bottom portion 13 of the chamber 10. The chamber 10 is open at its top end for permitting ejection of the column of ice as it forms within the chamber. The outer wall 14 of the housing 8 is spaced from the metal tubular element 9, and the space therebetween is filled with a suitable heat-insulating material. The top of the ice-making structure 6, except for the open end of the chamber 10, is closed by an annular member 15 of plastic or other suitable material of low heat conductivity. Refrigerant-conducting tubing 16 is coiled about and secured to the wall of the tubular element 9 for refrigerating this wall and, hence, for cooling the chamber 10 to freeze ice therein. Since the ring 12 which forms the bottom portion of the chamber and upon which the metal tubular element 9 rests is made of a material of low heat conductivity, the lower wall of the chamber is thermally isolated from the refrigerated element 9.

Water is supplied to the bottom 13 of the chamber 10 through a conduit 17 from a suitable source of supply. Water may be stored within

the inverted bottle 18 and supplied to the conduit 17 through a tray 19 mounted on the base 1 by legs 19a. The mouth of the bottle is submerged in the water in the tray 19 and the bottle rests on a gasket 19b having a conventional passage for entry of air. During operation of the apparatus a column of ice 20 is formed within the chamber 10. In order to move this column of ice upwardly so that its upper end projects an increasing distance above the top of the chamber 10, a rotatable cam or disc 21 is positioned in the bottom portion of the chamber 10. The cam 21 is the same diameter as the internal diameter of the chamber 10 and includes a raised portion 22 on its upper surface extending, as shown in Fig. 5, diametrically across this upper surface. The cam 21 is mounted on a vertical shaft 23 and rotates about the vertical axis of the shaft. A bushing or gland 24 is provided for sealing the shaft where it passes through the housing 8 and for acting as a bearing surface. The cam 21 is driven by a motor 25 through a gear reduction unit 26, a pulley 27, a belt 28, and a pulley 29. The gear reduction unit is employed for reducing the speed of the conventional motor 25 to a lower speed suitable for the operation of the cam 21. The belt and pulley arrangement also reduces the speed to some extent but is introduced primarily to provide for slippage should the cam 21 jam in the ice column 20 so that excessive strain is not imparted to the gears in the gear reduction unit 26. To prevent rotation of the ice column 20 with the cam so that rotation of the cam can be employed to force the ice column upwardly, the inner wall of the metal tubular element 9 is formed to provide a plurality of longitudinally extending grooves 29a. While the structure has been illustrated with grooves formed in the inner wall of the metal tubular element 9, it will be obvious that the same effect could be accomplished by forming this wall so as to provide inwardly extending longitudinal ridges in lieu of the grooves 29a. To conduct water from the bottom 13 of the chamber to the area immediately above the major portion of the upper surface of the cam 21, the cam is formed with a plurality of passages 30 extending therethrough.

The operation of the apparatus is illustrated more clearly in the enlarged view shown in Fig. 4. Referring to this figure, it can be seen that water from the conduit 17 is supplied to the bottom portion 13 of the chamber and passes through the passages 30 in the cam 21 to the region 31 directly above the major portion of the upper surface of the cam 21. A continuous column of ice 20 has been formed within the chamber 10 because of the refrigerated wall 9 thereof. This ice column extends down to and rests upon the raised portion 22 of the cam 21. A body of unfrozen water 20a remains in the body central portion of the ice column 20 because of the insulating effect of the surrounding ice. This raised portion 22 spaces the ice column 20 above the major portion of the upper surface of the cam 21 so as to provide the region 31 to which water is supplied and in which it is maintained. The cam 21 rotates relatively slowly, about 20 to 30 revolutions per minute, thus completely sweeping over the bottom surface of the ice column 20 once every 2 to 3 seconds. It engages the ice column only along the relatively small area of the raised portion 22, and the remainder of the bottom surface of the ice column is in contact with the water within the region 31. The water in the region 31 freezes onto the bottom of the ice

column 20 in a thin layer, which is only a few thousandths of an inch thick. This thin layer, of course, continuously builds up along the bottom of the ice column below a horizontal line 5 extending tangent to the top of the raised portion 22 and on the surface of the ice column located at the time between the diametrically opposite sections of the raised portion 22. Thus, by way of illustration, the bottom surface of the ice column may be in the shape shown on an exaggerated scale in Fig. 4. Hence, as the cam rotates, the raised portion 22 continuously encounters a portion of the ice column which extends slightly below the horizontal line extending tangent to the top of the raised portion 22, and the cam therefore raises the ice column by the amount of this layer. The amount of the ice column projecting beyond the top of the chamber 10 will therefore be increased during each revolution of the cam. The ice projecting above the top of the chamber 10 may be broken off in any desired manner, for example, by a heated wire moved across the ice column, by a plurality of prongs forced into the column, or by any other arrangements well known in the art.

It can be seen that by the arrangement described ice may be continuously formed in a cylindrical shape by employing a cam continuously rotating in one plane. The drive is simplified by being entirely rotary and not requiring a reciprocating piston nor does it require a continuously advancing piston which must ultimately be retracted for starting a new cycle.

While I have shown and described a specific embodiment of my invention, I do not desire my invention to be limited to the particular construction shown and described and I intend, by the appended claims, to cover all modifications within the spirit and scope of my invention.

What I claim as new and desire to secure by Letters Patent of the United States is:

1. Apparatus for continuously producing ice comprising means defining an upwardly extending chamber having an open top, means for continuously supplying water to said chamber at the bottom portion thereof, means for refrigerating said chamber to freeze said water into a column of ice, a rotatable cam disposed near bottom of said chamber and directly and continuously engaging the bottom of said ice column, and means for continuously rotating said cam in the same direction to lift said ice column, said water-supplying means causing water to flow into said chamber below said ice column as said ice column is continuously raised by said cam.

2. Apparatus for continuously producing ice comprising means defining an upwardly extending chamber having an open top, a rotatable disk disposed near the bottom of said chamber, means for continuously supplying water to said chamber above the lowermost portion of the upper surface of said disk, means for refrigerating said chamber to freeze said water into a column of ice, said disk being rotatable about an upwardly extending axis and having a raised portion on its upper surface for lifting said ice column, said raised portion directly engaging the bottom of said ice column, and means for continuously rotating said disk to lift said ice column, said water-supplying means causing water to flow into said chamber above said lowermost portion of said upper surface of said disk and below said ice column as said ice column is continuously lifted by said disk.

3. Apparatus for continuously producing ice comprising means defining an upwardly extend-

ing chamber having an open top, a rotatable disk disposed near the bottom of said chamber, means for continuously supplying water to said chamber above the lowermost portion of the upper surface of said disk, means for refrigerating said chamber to freeze said water into a column of ice, said disk being rotatable about an upwardly extending axis and having an irregular upper surface for lifting said ice column, said irregular upper surface directly engaging the bottom of said ice column, and means for continuously rotating said disk to lift said ice column, said water-supplying means causing water to flow into said chamber above said lowermost portion of said upper surface of said disk and below said ice column as said ice column is continuously raised by said disk.

4. Apparatus for continuously producing ice comprising means defining an upwardly extending chamber having an open top, means for continuously supplying water to said chamber at the bottom portion thereof, means for refrigerating said chamber to freeze said water into a column of ice, a rotatable cam disposed near the bottom of said chamber and directly and continuously engaging the bottom of said ice column, means for continuously rotating said cam in the same direction to lift said ice column, said water-supplying means causing water to flow into said chamber below said ice column as said ice column is continuously raised by said cam, and means for preventing rotation of said ice column.

5. Apparatus for continuously producing ice comprising means including a wall defining an upwardly extending chamber having an open top, a rotatable cam disposed near the bottom of said chamber, means for continuously supplying water to said chamber at the bottom portion thereof, means for refrigerating said chamber to freeze said water into a column of ice, and means for continuously rotating said cam to lift said ice column, said wall of said chamber having a longitudinal groove therein for preventing rotation of said ice column, said water-supplying means causing water to flow into said chamber below said ice column as said ice column is continuously raised by said cam.

6. Apparatus for continuously producing ice comprising means including a wall defining an upwardly extending chamber having an open top, a rotatable cam disposed near the bottom of said chamber, means for continuously supplying water to said chamber at the bottom portion thereof, means for refrigerating said chamber to freeze said water into a column of ice, and means for continuously rotating said cam to lift said ice column, said chamber having a longitudinally extending portion laterally displaced from the remainder of said wall for preventing rotation of said ice column, said water-supplying means causing water to flow into said chamber below said ice column as said ice column is continuously raised by said cam.

7. Apparatus for continuously producing ice comprising means defining an upwardly extending chamber having an open top, a rotatable cam disposed near the bottom of said chamber, means for continuously supplying water to the bottom of said chamber below said cam, said cam having a passage therethrough for conducting water from

the bottom of said chamber to the region above a portion of said cam, means for refrigerating said chamber to freeze said water into a column of ice, and means for continuously rotating said cam to lift said ice column, water supplied through said passage in said cam to said region being frozen as successive layers on the bottom end of said ice column.

8. Apparatus for continuously producing ice comprising means defining an upwardly extending chamber having an open top, a rotatable cam disposed near the bottom of said chamber, means for continuously supplying water to said chamber in the region above a portion of said cam, means for refrigerating said chamber to freeze said water into a column of ice, said cam directly and continuously engaging the bottom of said ice column, and means for continuously rotating said cam in the same direction about an axis aligned with the axis of said ice column to lift said ice column, water supplied to said region being frozen as successive layers on the bottom end of said ice column.

9. Apparatus for continuously producing ice comprising means defining an upwardly extending chamber having an open top, a rotatable cam disposed near the bottom of said chamber, means for continuously supplying water to the bottom of said chamber below said cam, said cam having a passage therethrough for conducting water from the bottom of said chamber to the region above a portion of said cam, means for refrigerating said chamber to freeze said water into a column of ice, means for preventing rotation of said ice column, and means for continuously rotating said cam in the same direction to lift said ice column, water supplied through said passage in said cam to said region being frozen as successive layers on the bottom end of said ice column.

10. Apparatus for continuously producing ice comprising means including a wall defining an upwardly extending chamber having an open top, a rotatable cam disposed near the bottom of said chamber, means for continuously supplying water to the bottom of said chamber below said cam, said cam having a passage therethrough for conducting water from the bottom of said chamber to the region above a portion of said cam, means for refrigerating said chamber to freeze said water into a column of ice, said wall of said chamber being formed to provide a longitudinal groove for preventing rotation of said ice column, means for continuously rotating said cam to lift said ice column, water supplied through said passage in said cam to said region being frozen as successive layers on the bottom end of said column.

ALFRED G. JANOS.
